UNITED STATES PATENT OFFICE.

ROBERT F. WRIGHT AND THOMAS E. WRIGHT, OF CIRCLEVILLE, OHIO.

RUBBING-POST.

1,080,037.

Specification of Letters Patent.

Patented Dec. 2, 1913.

Application filed January 30, 1913. Serial No. 745,188.

To all whom it may concern:

Be it known that we, ROBERT F. WRIGHT and THOMAS E. WRIGHT, citizens of the United States, residing at Circleville, in the county of Pickaway and State of Ohio, have invented certain new and useful Improvements in Rubbing-Posts, of which the following is a specification.

The present invention relates to an improved rubbing post adapted especially for antivermin treatment in animal husbandry.

The primary object of the invention is the provision of an oiling post against which hogs may rub themselves for antivermin treatment, and the construction of existing oiling posts is improved in certain particulars as will be hereinafter pointed out.

In the accompanying drawings we have illustrated one complete example of the physical embodiment of our invention constructed according to the best mode we have so far devised for the practical application of the principles of the invention.

Figure 1 is a view in elevation of an oiling post involving our invention. Fig. 2 is a vertical sectional view of part of Fig. 1.

In the preferred embodiment of our invention we utilize the post 1 provided with a base 2 through the medium of which the post may be securely anchored against movement due to pushing or rubbing of the animals. A reservoir or tank 3 is mounted above the post in which oil is contained, and the reservoir is equipped with a suitable number of valved nozzles 4, four being indicated in the drawings, although it will of course be understood that this number may be varied within limits as described. A top 5 is located on the tank and is secured thereon by means of the pin 6 which moves in the bayonet slot 7 indicated in dotted lines.

In the drawings we have illustrated a conventional valved nozzle or nipple which is screwed into a perforation at the bottom 45 of the tank. It will be understood that we may use other suitable forms of nozzles, but however changed the form may be, we in any event provide a hood or shield 8. It will also be understood that the handles 9, 50 illustrated in the drawings as permanently secured to the nozzles may be dispensed with and all the nozzles controlled and regulated by one and the same tool or key, which is applied only when needed. The

hoods or shields are to prevent ingress of rain or snow to the closure of the nozzle end which is normally closed by means of a lever 10. Inasmuch as each of the levers 10 is similar to the others, a description of one lever will apply to all. The lever 10 is pivoted by rivet 11 in the post, and its upper arm 12 has secured to its inner face a packing disk 13 of leather, rubber, or other suitable material, adapted to close over the open end of the nozzle 4. The nozzle is normally closed by the lever through the action of the spring 14 which is interposed between the post and the lower arm 15 of the lever. The inner side of the arm 12 is provided with a channel formed by the wings or side flanges 16, and this channel extends downwardly past the pivot until it merges into an orifice or passage 17 through the upper part of the arm 15. The presence of the passage 17 forms a shoulder 75 or abutment 18, so that it will readily be seen that when the nozzle 4 is open oil may flow from the tank through the nozzle down the channel between the flanges 16 and out to the front of the arm 15 through the passage 17, the wall 18 preventing the oil from flowing down the inner surface of the arm 15. The outer surface of the arm 15 is corrugated, as indicated at 19. These corrugations not only provide a roughened surface 85 against which the hog may rub, but they form ducts or canals for the distribution and retention of the oil as it flows from the nozzle. Because of the presence of the corrugations, the oil is prevented from running 90 off the arm as would be the case with smooth surface, and the oil is also uniformly distributed over the face of the arm. The lower end of the arm is projected, as at 20, from the plane of the arm, by means of 95 which a hog may rub himself in otherwise inaccessible places.

The operation of the device will be readily understood. The small or weaker pigs press against the lever where the leverage is greatest, the larger and stronger ones rub where the leverage is less, but the applied power is greater. Pushing in the arm 15 opens the nozzle 4 so that oil may flow to the outer face of the lower arm 15 as described, and 100 for the purpose specified. The flow of oil from the tank may of course be regulated by the valved nozzles, and the leather pack-

ing will prevent leaks, while the hood or shield 8, as before described, keeps out rain, snow, or other extraneous harmful agencies.

Having thus described our invention, what we claim as new is:—

An oiling post comprising a tank and a nozzle, a spring pressed lever having an arm to close the nozzle and side flanges forming a channel which merges into a central distributing orifice through the lever, said lever having a comparatively broad rubbing sur-

face below the orifice, and formed with a rounded protuberance at its lower end to be engaged by the underside of an animal's body.

15

In testimony whereof we affix our signatures in presence of two witnesses.
